ELECTRIC IGNITION AND AUTOMATIC PILOT FOR GASEOUS FUEL BURNERS

Samuel George Eskin, Los Angeles, Calif., assignor
to Robertshaw-Fulton Controls Company,
Youngwood, Pa., a corporation of Delaware

Application May 4, 1948, Serial No. 24,936

1 Claim. (Cl. 158—128)

1

This invention relates to control and ignition systems for fuel burners and, more particularly, to combined thermoelectric pilot control and electric ignition apparatus for domestic gas ranges.

It has long been recognized that electric ignition and control systems are desirable for gas range ovens provided such apparatus can be manufactured and sold without too great expense. Electric ignition permits realization of the so-called "cold" oven and is not as dependent upon uniform quality of gas as are most flash tube systems. Automatic pilot controls have in large part depended upon relatively expensive time delay and other electrically operated devices which have retarded acceptance for use on domestic ranges due to initial cost and upkeep expense.

An object of this invention is to combine electric ignition and automatic pilot control in a relatively inexpensive and simple arrangement applicable to domestic gas ranges.

Another object of the invention is to utilize electric energy from a commercial source for oven ignition purposes only and to discontinue consumption of such energy during normal operation of the oven.

Another object of the invention is to eliminate special time delay mechanisms and electrically operated valves.

Another object of the invention is to facilitate servicing of the apparatus when installed on a range and permit ready access to the component parts.

Other objects and advantages will become apparent from the following description taken in connection with the accompanying drawing which is a schematic view of an oven burner installation having the control and ignition system applied thereto.

Referring more particularly to the drawing, an oven 18 shown in broken lines in the drawing is provided with a main burner 12 and a pilot burner 14 located in lighting proximity thereto. The flow of fuel is conducted to the main burner 12 by a main fuel pipe 16 under control of the usual combined oven thermostat and gas shut-off cock 18 to which a conduit 20 for supplying fuel to the pilot burner 14 is connected. As is customary in such control devices, the manual rotation of the shut-off cock 18 to closed position will shut off flow of fuel in both the main fuel pipe 16 and the conduit 20, but operation of the combined thermostat when satisfied will serve to shut off fuel in the main fuel pipe 16

only. As such devices are well known, further description is deemed unnecessary.

Interposed in the main fuel pipe 16 between the shut-off cock 18 and the main burner 12 is the automatic pilot control device 22 previously mentioned. The device 22 comprises a hollow casing 24 having an inlet 26 and an outlet 28 to which opposite ends of the main fuel pipe 16 are connected respectively. A partition 30 extending across the interior of the casing 24 serves to separate the inlet 26 from the outlet 28 so that flow of fuel therebetween is permitted only by way of an axial opening 32 formed in the partition 30.

The flow of fuel through the opening 32 is under control of a control means shown as a valve member 34 which is adapted to be seated on the side of the partition 30 adjacent the inlet 26. The valve member 34 is provided with a stem 36 which extends through an apertured partition 38 and carries an armature member 40 on its projecting end. A coil spring 41 is operative between the valve member 34 and the apertured partition 38 for biasing the valve member 34 toward its seat on the partition 30 to establish the closed position of the valve member 34.

The armature member 40 forms part of an electromagnetic means and is adapted for movement between attracted and released positions relative to the pole faces of a horseshoe magnet 42 according to the energization or deenergization respectively of a winding 44 associated with the magnet 42. Due to the provision of the coil spring 41, the armature member 40 is biased to its released position and resetting means to be described hereinafter are employed to place it in the attracted position. The winding 44 is energized by the thermoelectric current generated by a thermocouple 46 which is electrically connected to the winding 44 and is located to be heated by a flame at the pilot burner 14. It will be understood that the energy so generated is insufficient to attract the armature 40 from its released position but is sufficient to retain it in the attracted position upon completion of the resetting operation.

The reset means comprise a reset stem 48 which extends exteriorly of the casing 24 at the end opposite the magnet 42. The inner end of the reset stem 48 extends axially through the opening 32 and terminates adjacent the valve member 34. A closure disc 50 is carried on the reset stem 48 for seating upon the underside of the partition 30 to interrupt the flow of fuel

through the opening 32 when the valve member 34 is disengaged from its seat during the resetting operation. It will be understood that where the pilot burner 14 is dispensed with and the thermocouple 46 made responsive to the flame from the main burner 12, that the closure disc 50 could be omitted. It will further be understood that the casing 24 and associated parts are shown in schematic form herein and suitable provision would be made in commercial structures for leakage prevention and other necessary requirements not forming part of the essential arrangement herein disclosed.

The ignition system of this invention comprises an igniter 52 in the form of a coil of wire of suitable electrical resistivity which is positioned to ignite the fuel issuing from the pilot burner 14 when the wire is brought to igniting temperature. The igniter is adapted to be energized for such purpose from a suitable source of electric energy such as the domestic current supply. To this end, a transformer 54 is provided in this embodiment and has its primary coil connected at one end to a line wire 56 and the opposite end connected to a line wire 58. One terminal of the secondary coil of the transformer 54 is connected by a wire 60 to one terminal of the igniter 52 while the other terminal of the secondary of transformer 54 is connected by a wire 62 to the opposite terminal of the igniter 52. Since the igniter 52 need only be energized during the resetting operation, suitable switching means are employed in the described series circuit to maintain the circuit normally open. To this end, the reset stem 48 is provided with an enlarged head 64 positioned exteriorly of the casing 24. A coil spring 66 is operative between the enlarged head 64 and the underside of the casing 24 to retain the reset stem 48 in an outwardly projected position with the closure disc 50 spaced from the partition 30. A single pole switching device is incorporated in the enlarged head 64 by the provision of a recess 68 therein within which a pair of resilient switch arms 70 are positioned with their oppositely curved ends 71 in spaced relation. The opposite ends of the resilient switch arms 70 are connected to opposite ends of the wire 60 in series circuit arrangement.

A momentary-contact push-button 72 is reciprocal relative to the enlarged head 64 into engagement with the curved ends 71 of the resilient switch arms 70 for closing the igniter circuit. The push button 72 projects through a partition 74 extending across the recess 68 and providing a bearing for the button 72. A collar 76 carried by the push button 72 is engaged on one side by a flange 78 formed on the enlarged head 64. Such engagement prevents ejection of the push button 72 from the enlarged head 64 under bias of a coil spring 80 which is operative between the opposite side of the collar 76 and the underside of the partition 74. The projecting end of the push button 72 beyond the flange 78 is adapted to be engaged by the operator for axial movement of the push button 72 relative to the reset stem 48. It will be understood that suitable provision for insulation, terminal connections and other common electrical requirements will be provided in the commercial form of switch.

In the operation of the device described, the parts may be assumed to be in the position shown in the drawing with the shut-off cock 18 occupying an off position to prevent flow of fuel to

the main burner 12 and the pilot burner 14. Rotation of the shut-off cock 18 to an open position will simultaneously set the temperature at which the oven thermostat combined therewith will operate. Fuel is thus permitted to flow through the conduit 20 to the pilot burner 14.

Manual operation of the reset stem 48 is then conducted by pressure applied to the enlarged head 64 and simultaneously to the push button 72. Such operation serves to close the circuit to the igniter 52 by engagement of the push button 72 with the resilient switch arms 70. Moreover, the axial movement of the reset stem 48 serves to disengage the valve member 34 from the partition 30 and also to seat the armature member 40 against the pole faces of the magnet 42. However, due to the simultaneous seating of the closure disc 50 on the partition 30, the flow of fuel in the pipe 16 to the main burner 12 is interrupted during this resetting operation.

The igniter 52 quickly reaches igniting temperature and serves to ignite the fuel flowing from the pilot burner 14. The thermocouple 46 becomes heated by the flame at the pilot burner 14, thus energizing the winding 44 sufficiently to retain the armature 40 in its attracted position. The push button 72 and the reset stem 48 are returned to their outwardly projected positions upon release of manual pressure thereon, whereupon the igniter 52 is deenergized and the closure disc 50 no longer prevents flow of fuel to the main burner 12. Since the valve member 34 is now retained in open position due to the operation of the electro-magnetic means, the passage of fuel between the inlet 26 and outlet 28 is now established and such fuel flowing from the main burner 12 is ignited by the flame at the pilot burner 14. The apparatus is now in normal running condition with the main burner 12 under control of the oven thermostat incorporated with the shut-off cock 18.

Should the flame at the pilot burner 14 become extinguished, then the thermocouple 46 will cool serving to deenergize the winding 44 and release the armature member 40 for movement under bias of the coil spring 41. Since the armature 40 and the valve member 34 are connected by the valve stem 36 for joint operation, the valve member 34 is caused to become closed to shut off flow of fuel to the main burner 12.

It will be apparent that the single push operation described for ignition and resetting purposes can be varied at the will of the operator. For example, the system may be operated in such manner that only the pilot burner 14 is ignited and no resetting operation occurs until a later time. In this method of operation the shut-off cock is opened to a set temperature for the oven 10 and the push button 72 is pushed in and held for about three seconds. The enlarged head 64 remains unoperated at this time so that the safety valve member 34 remains seated and no fuel flows to the main burner. The igniter 52 being energized the fuel at the pilot burner 14 is ignited and the thermocouple 46 becomes heated. The oven burner 10 can be supplied with fuel at any time after the thermocouple 46 is heated in the discretion of the operator by merely operating the enlarged head 64. This member may immediately be released and the main burner 10 will ignite instantaneously.

Since the apparatus described is provided with the closure disc 50 which is operated by movement of the reset stem 48, the igniter 52 can immediately be reenergized after a period of

burner operation. In such restarting operation the thermocouple 46 remains heated and the valve member 34 is held in the open position due to continued energization of winding 44. Accordingly, the shut-off cock is rotated to open position and the reset stem 48 is manually operated as previously described. No fuel can flow to the main burner 12 at this time due to the seating of the closure disc 50 but the fuel flowing from the pilot burner 14 is ignited. As the thermocouple 46 is already heated, no additional waiting period is required and main burner operation immediately occurs upon release of the manual pressure. Thus, an instantaneous reset has been accomplished without special time delay devices.

An obvious modification would be to remove the push button 72 from the described location on the enlarged head 64 and dispense with the separate operation of the igniter 52. In this modified form, the relatively fixed contact means, comparable to the switch arms 78, could be carried by the casing 24 for engagement by relatively movable contact means, comparable to the push button 72, and carried on the enlarged head 64 but not movable relative thereto. In such event, the operation of the reset stem 48 would also serve to energize the igniter 52 with a single push motion.

These and other changes may be made in the details of construction and arrangement of parts within the scope of the appended claim and the invention is not limited to the precise embodiment shown and described herein.

I claim:

In a control and ignition system for fuel burning apparatus having main and pilot burners and a source of electric energy, the combination of an electric igniter for the pilot burner connected to be energized from the source, a casing having a fuel inlet and an outlet to the main burner, a valve member reciprocable in said casing for controlling the flow of fuel between said inlet and outlet, thermoelectric means responsive to a flame at the pilot burner, electromagnetic means having a coil member and an armature member con-

nected to the thermoelectric means for energization thereby sufficiently to hold said armature in attracted position relative to said coil member but insufficiently to cause movement of said armature member from a released position, means operable between said casing and valve member for biasing the latter to closed position, connecting means between said armature and valve members for joint movement therebetween, a reset stem extending exteriorly of said casing and being axially movable by manual operation relative to said casing from an initial position into operative position for overcoming said bias and resetting said armature member in said attracted position and said valve member in an open position, means carried by said reset stem for interrupting the flow of fuel between said inlet and outlet during the resetting operation, a normally open switch controlling energization of said igniter and having an operating portion carried by said reset stem for movement independently thereof to closed position when said armature member is moved to said attracted position, means for biasing said reset stem to said initial position upon cessation of said manual operation, and means for biasing said switch to open position for de-energizing said igniter upon completion of said resetting operation.
